J. SCHIRRA,
VACUUM CLEANING APPARATUS.
APPLICATION FILED AUG. 28, 1911.

1,174,616.

Patented Mar. 7, 1916.

UNITED STATES PATENT OFFICE.

JULIUS SCHIRRA, OF PITTSBURGH, PENNSYLVANIA, ASSIGNOR TO HAND VACUUM SWEEPER COMPANY, OF PITTSBURGH, PENNSYLVANIA, A CORPORATION OF PENNSYLVANIA.

VACUUM CLEANING APPARATUS.

1,174,616.

Specification of Letters Patent.

Patented Mar. 7, 1916.

Original application filed May 10, 1911, Serial No. 626,274. Divided and this application filed August 28, 1911. Serial No. 646,340.

To all whom it may concern:

Be it known that I, JULIUS SCHIRRA, a citizen of the United States of America, residing at Pittsburgh, in the county of Allegheny and State of Pennsylvania, have invented certain new and useful Improvements in Vacuum Cleaning Apparatus, of which the following is a specification, reference being had therein to the accompanying drawing.

My invention relates to improvements in vacuum cleaning apparatus, and has particular relation to the manner of attachment of the suction head to the suction device.

The present application is a division of the application filed by me May 10, 1911, Serial No. 626,274 (patented Nov. 7, 1911, #1008205).

The principal object of my invention is to provide a device of this character in which the suction head is secured to the forward end of the suction device, the inlet opening for the material being positioned off center of the head, means being provided for removably securing the suction head to the head of the suction device with proper connections between the suction orifice and the inlet opening.

A further object is to provide means whereby the suction head will be operatively connected to the suction device with the inlet into the latter off center while the head is supported at a point axially of the suction device.

Other and further objects of the invention are to provide a device of this character which is simple and efficient in operation, durable in construction, which may be readily attached to the handle of a household utensil, and which can be manufactured at a relatively low cost.

To these, and other ends, the nature of which will be readily understood as the invention is hereinafter disclosed, my invention consists in the improved construction and combination of parts hereinafter fully described, illustrated in the accompanying drawings, and particularly pointed out in the appended claims.

In the accompanying drawings, in which similar reference characters indicate similar parts in each of the views—Figure 1 is a perspective view of a vacuum cleaning ap-

paratus, of which my invention forms a part. Fig. 2 is a central longitudinal sectional view of the parts shown in Fig. 1, the suction device being shown as broken away. Fig. 3 is a sectional view illustrating a modified form of suction head connection employed when the structure is applied to a carpet sweeper.

The particular construction of the suction device, shown at the right in Figs. 1 and 2, is not herein specifically described, as it forms the subject-matter of the claims of the application above identified, the only portions thereof which pertain to the present invention being the handle 10 and the plate 13 of the end cap 12, said plate forming the forward end of the suction device and having the valved inlet and discharge openings, the latter communicating with the dust collector 21.

The handle 10 extends axially of the suction device and preferably projects forwardly from the plate 13, this forwardly projecting portion acting as a means for supporting the suction device with respect either to the suction head, as shown in Figs. 1 and 2, or to a device on which the suction head is supported, as for instance, a carpet sweeper, the arrangement shown in Fig. 3, the projecting portion being preferably central of the head or plate 13. The inlet to the suction device is in the form of a cylindrical projection 18 which is adapted to receive the connection from the suction head, this inlet being arranged off center, the port being controlled by a valve 19 of suitable type and adapted to operate in accordance with the requirements of use.

The suction head shown in Figs. 1 and 2 is substantially non-flexible, being in the form of a tubular member 29 having its rear end adapted to be passed over the projection 18, and having its forward end secured to or forming a part of the suction head 30, the latter having a member 31 which is adapted to be passed over the projecting end of the handle 10 and acting as a continuation of the handle to support the suction head.

The structure of Fig. 3 is that employed by me in the construction disclosed in my companion application filed February 9, 1911, Serial No. 607,456 (patented Nov. 14, 1911, #1008865), in which the device is shown as in operative relation to and as an

attachment for carpet sweepers. In this view the bail of the sweeper is indicated at 11, the sweeper body being indicated at 1, and being shown as supporting a suction head 2 in advance of the sweeper body, the suction head being connected to projection 18 by a flexible connection 28, said connection being removably secured to the projection. The connection between the sweeper 10 and the lower end of handle 10 is a removable one, so that by disengaging both bail and connection 28 from the suction creating mechanism, the nozzle shown in Fig. 2 can be readily substituted.

15 The particular structure of parts is such that either type may be used in connection with the plate 13 and handle 10. When the device of Fig. 3 is employed, the forward end of the handle is threaded into the bail 20 of the sweeper or secured in a socket carried by such bail, and the connection between the head and the inlet port is mounted on the projection 18, the suction head itself being carried by the sweeper. In the construction 25 shown in Figs. 1 and 2, the head and support are non-flexible and are also connected to the same two parts of the plate, viz., the handle and the projection 18. In either form the construction is such that the handle 30 through the extension thereof provided by the member 31 or the bail of the sweeper, in effect extends substantially to the suction head so that the handle acts to provide the necessary movements to the head, relieving 35 the conduit connection between the head and the suction device from the pressures produced by such movements, thereby permitting of the use of flexible or non-flexible conduit connections between the suction head 40 or nozzle and the suction device at will according to the character of the support employed for the head or nozzle, the conduit connections being relieved from the pressure provided in moving the apparatus about in 45 operation, such pressures being generally central and in a direct line and applied from the handle to the head or nozzle through the supporting connection therebetween, such latter connection being sufficiently rigid to 50 provide for this application of the pressures.

As will be seen, the arrangement herein disclosed provides substantially two general elements, one being the carpet sweeper for providing a sweeping action, the other being 55 means for creating and applying suction cleaning action, the latter including the two types of suction head and connections. When the parts are connected as shown in Fig. 3, the suction-creating mechanism acts 60 to provide the to and fro movements to the sweeper, it being understood that the handle 10 forms a portion of such mechanism, in which case the combined or separate move-

ments of the sweeper and suction-cleaner may be had as set forth in my said prior 65 Patent No. 1,008,865. Owing to the fact, however, that the suction-creating mechanism is removed from the sweeper as a unit, and the connection 28 detachable from the suction-creating mechanism, it will be obvious 70 that the employment of the nozzle structure of Fig. 1, will enable suction-cleaning action to take place separate from the sweeper, thus enabling cleaning action to take place at points inaccessible to the 75 sweeper itself, as for instance, on stairways, etc. This result is due to the ability to separate the sweeper and suction-creating mechanism and the detachability of the suction head or nozzle from the suction-creat- 80 ing mechanism.

While I have herein disclosed several ways in which my invention may be carried into effect, I am aware that changes and modifications therein may be necessary to 85 meet the various exigencies of use, and I reserve the right to make any and all such changes and modifications as may be found necessary in-so-far as they may fall within the spirit and scope of the invention as here- 90 inafter pointed out in the claims.

Having thus described my invention, what I claim as new is:—

1. In combination, suction-creating mechanism, a carpet sweeper, and a suction nozzle, said nozzle being positioned in advance of the sweeper body and having a removable connection with said mechanism, said mechanism and sweeper being detachably connected together, whereby said parts may 95 travel as an entirety in the to and fro movements of the sweeper, said mechanism extending above the sweeper and being detachable bodily from the nozzle and sweeper.

2. In combination, a carpet sweeper, a suction-creating mechanism detachably connected to and movable with the sweeper body during the to and fro movements thereof, and a suction nozzle in advance of the sweeper body, said mechanism having 100 means above the plane of the top of the sweeper body for detachably connecting the nozzle thereto.

3. In combination, a carpet sweeper, suction-creating mechanism removably connected to and positionable to extend over the sweeper, said mechanism having means whereby a dust-inlet nozzle may be removably connected thereto to complete a suction-cleaning device.

In testimony whereof I affix my signature in the presence of two witnesses.

JULIUS SCHIRRA.
